ELECTRIC BLENDER BASE

Paul O. Rawson, Trumbull, Conn., assignor, by mesne assignments, to Dynamics Corporation of America, New York, N.Y.

Filed Aug. 24, 1964, Ser. No. 81,419

Term of patent 14 years

(Cl. D89—1)

FIG. 1 is a front view of an electric blender base showing my new design;

FIG. 2 is a bottom view;

FIG. 3 is a side elevational view; and

FIG. 4 is a top plan view.

The essential features of the design are shown in full lines.

I claim:

The ornamental design for an electric blender base, as shown and described.
